UNITED STATES PATENT OFFICE.

FRANK YOKEL, OF CLEVELAND, OHIO, ASSIGNOR TO MARKEL ELECTRIC PRODUCTS, INC., OF BUFFALO, NEW YORK, A CORPORATION OF NEW YORK.

DESIGN FOR A HUSK FOR INCANDESCENT LAMPS.

Application filed April 27, 1927. Serial No. 21,745. Term of patent 3½ years.

To all whom it may concern:

Be it known that I, FRANK YOKEL, a citizen of the United States, residing at Cleveland, in the county of Cuyahoga and State of Ohio, have invented a new, original, and ornamental Design for Husks for Incandescent Lamps, of which the following is a specification, reference being had to the accompanying drawing, forming part thereof.

In said drawing:

Figure 1 is a side elevation of a husk for an incandescent lamp showing my new design.

Figure 2 is a bottom plan view of the same showing detail in full lines and indicating repetition of detail in broken lines.

I claim:

The ornamental design for a husk for incandescent lamps as shown.

FRANK YOKEL.
